UNITED STATES PATENT OFFICE.

ISAAC E. PALMER, OF MIDDLETOWN, CONNECTICUT.

DESIGN FOR A HAMMOCK.

SPECIFICATION forming part of Design No. 29,455, dated October 4, 1898.

Application filed September 2, 1898. Serial No. 690,137. Term of patent 14 years.

To all whom it may concern:

Be it known that I, ISAAC E. PALMER, a citizen of the United States, and a resident of Middletown, in the county of Middlesex and State of Connecticut, have invented and produced a new and original Design for Hammocks, of which the following is a specification, reference being had to the accompanying drawings, forming a part thereof.

The leading feature of my design consists in a hammock provided with double rows of ornamentation, each row being made to substantially conform to the other row and the ornamental figures of one row being made more plainly visible than the corresponding ornamental figures of its companion, by which a shadow effect is produced.

In the accompanying drawings, Figure 1 represents the hammock as it appears when

spread out in a plane, and Fig. 2 is a side view of the hammock as it appears when strung for use.

The lines of plainly-visible ornamental figures are denoted by A, and the corresponding lines of figures, less plainly visible and which produce the shadow effect, are denoted by a.

What I claim is—

The design for a hammock, substantially as herein shown and described.

In testimony that I claim the foregoing as my invention I have signed my name, in presence of two witnesses, this 31st day of August, 1898.

ISAAC E. PALMER.

Witnesses:

I. B. LALLAUDE,
E. B. WETMORE.
